FREDERICK ALEXANDER WARD, OF DETROIT, MICHIGAN, ASSIGNOR TO GEAR
GRINDING MACHINE COMPANY, OF DETROIT, MICHIGAN, A CORPORATION OF
MICHIGAN.

TRIMMING MECHANISM FOR GRINDER-WHEELS OF SHAFT-GRINDING MACHINES.

1,155,532.

Specification of Letters Patent.

Patented Oct. 5, 1915.

Application filed August 13, 1912. Serial No. 714,811.

To all whom it may concern:

Be it known that I, FREDERICK A. WARD, a citizen of the United States of America, residing at Detroit, in the county of Wayne 5 and State of Michigan, have invented certain new and useful Improvements in Trimming Mechanism for Grinder-Wheels of Shaft-Grinding Machines, of which the following is a specification, reference being had 10 therein to the accompanying drawings.

The invention relates to trimming mechanism for grinder wheels of shaft grinding machines, and has for its object the obtaining 15 of a construction adapted to accurately grind interrupted or obstructed cylindrical surfaces.

More particularly, it is the object of the invention to provide means for trimming a grinder to adapt the same for grinding 20 spline shafts, such as are used in the construction of sliding gear transmission mechanisms and for similar purposes.

In the drawings: Figure 1 is a side elevation of the machine. Fig. 2 is a side elevation 25 of one member of the trimming mechanism. Fig. 3 is a sectional end elevation thereof. Fig. 4 is a longitudinal section through another member of the trimming mechanism. Fig. 5 is an end elevation thereof. Fig. 6 is a cross section showing the 30 grinder in engagement with the work.

My machine comprises broadly a work-holder and a grinder having a relative reciprocatory movement parallel to the axis of the work, an indexing mechanism for accurately adjusting the work rotatively, and a trimming mechanism by which the periphery of the grinder may be fashioned to the exact contour desired. This trimming 35 mechanism includes a concave trimmer the radius of which may be adjusted to correspond to the work, and edge trimmers in an accurately predetermined angular relation to each other, which limit the length of 40 the curve and fashion the surfaces for grinding the sides of the keys or splines. Both of these trimming devices are exactly 45 centered in the plane of the longitudinal axis of the work and are preferably arranged in axial alinement with the work so that the grinder may be moved directly from one to the other.

In detail, A is a supporting bed or frame,

upon which is mounted the reciprocatory work-table B and which is further provided 55 with an upward extension C, upon which a vertically adjustable head D is mounted carrying the arbor E for the grinder F.

G is a suitable work holder and indexing mechanism mounted upon the bed, it being 60 provided with a work holding center H adapted to coöperate with a similar work holding center H' upon a support G'. An adjustable clamp K is positioned on the end 65 of the work to drive the same, it having a releasable engagement through the medium of the lug J with a rotatable head I. The indexing mechanism may be of any suitable construction (not shown), being provided with means for intermittently rotating the 70 work through the desired angle, such as the crank handle L. Thus by suitably adjusting the mechanism the work may be successively partially rotated to present different segments to the action of the grinder. 75

The trimming mechanism comprises an arc trimmer M and edge trimmers N. The former is provided with a rotatively movable shaft O mounted in a bearing P, the axis of said shaft being in the same plane 80 as the longitudinal axis of the work.

Q is a diamond holder which engages a transversely extending recess in the shaft O and is adjustably secured in position by a set screw R. 85

S is a gage engaging a supporting arm or bracket S' and adjustably secured by a set screw S² in the transverse plane of the holder Q, the arrangement being such that by first setting the gage the diamond may be 90 adjusted by moving it into contact with the gage and then securing the holder by the set screw R.

The edge trimmer N comprises a pair of oppositely angling guide arms T and T', 95 upon which reciprocating heads U are mounted, being adjustable by suitable means such as the rack bars U², pinions U³ and operating wheels U⁴. Each of the heads U is provided with a diamond or other trimmer means holder V which is adjustable transversely of the head by suitable means such as a threaded engagement with a threaded socket. The arms T and T' are mounted upon a vertically adjustable shank 100 T² which is secured in a socket member W 105

upon the base, the arrangement therefor permitting of simultaneously adjusting both the arms T and T' vertically to change the relation to the trimmer M, and also permitting of exchanging the member having the arms T and T' where a different angular relation for the trimmers is desired. The vertical adjustment of the shank T² may be effected by an adjusting screw X engaging an ear X' and bearing against the base. With the construction of the trimming mechanism just described, where it is desired to prepare the machine for grinding a splined shaft, such for instance as shown in Fig. 6, the trimmers M and N are first set. The trimmer M may be set by adjusting the gage S in relation to the shaft Q, so that the distance from the axis of the shaft to the gage exactly corresponds to the radius of the cylindrical portion of the finished work. The diamond or trimming means is then adjusted to the gage. In adjusting the trimmer N a member having arms T and T' of the desired angle is first selected and engaged with the holding socket W, after which the holders V are properly adjusted in the reciprocatory heads U and the shank T² is vertically adjusted in the socket W. Where the diamond holders are adjusted with their cutting points the same distance from the guide arms T the setting of both guides is effected by the vertical adjustment of the shank T² by means of the adjusting screw X. Thus the two trimmers M and N will conjointly fashion the grinder medium to the exact form desired.

In trimming the wheel the table "B" is moved longitudinally to carry the diamond or other trimmer means holder to a central position under the grinding wheel arbor and the head "D" is adjusted to carry the arbor toward the trimmers until the periphery of the wheel is properly fashioned by the movement of the trimmers. The machine is then adjusted to reciprocate the work in relation to the grinder, and after each reciprocation the indexing mechanism is operated to rotatively adjust the work, whereby the different segments of the surface are successively ground. The operation is continued with a gradual adjustment of the head D until the center of the arc portion of the grinding surface coincides with the axis of the work, or in other words, until the cylindrical portion of the work is reduced to the proper size which may be determined by measurement. It is however desirable before finally finishing the work to re-trim the grinder so that during the finishing cut the grinder is of the exact complementary form.

While I have described the use of my machine for the specific purpose of grinding splined shafts, it is obvious that it is applicable for various other uses.

It is obvious that the required result may be accomplished by the reciprocation of either work or grinding medium and that in feeding to reduce the work to size either the work or grinding medium may be moved toward the other which has a fixed position.

The terms "cylindrical" and "arc" are used in the specification and claims generally as including other curves than a true circle.

What I claim as my invention is;

1. The combination with a rotary grinder wheel of a reciprocatory work-holder and trimming mechanism for said wheel, comprising a concave forming trimmer centered parallel to the longitudinal axis of said work-holder and provided with means for adjusting the radius of the arc, and an edge trimmer provided with divergent arms and trimming points movable on said arms.

2. In a machine of the character described, trimming mechanism for the grinder wheel, comprising a rotatable shaft having its axis of rotation parallel to the longitudinal axis of the work, a trimming point and a holder for the trimming point laterally, adjustably secured to said rotatable shaft, and a second trimmer provided with divergent guide arms and trimming points movable along said guide arms for the purpose described.

3. The combination with a rotary grinder wheel and a relatively reciprocatory work-holder of a trimming mechanism for the grinder wheel, comprising a rotatable member having its axis parallel to the longitudinal axis of the work, a radial adjustable trimming-point holder secured to said rotatable member and an exchangeable trimmer having divergent guide arms and trimming points movable thereon, said guide arms being adjustable in relation to the axis of the rotative trimmer for the purpose described.

4. The combination with a rotary grinder wheel and a relatively reciprocatory work-holder, of a trimmer, comprising a rotatable member having its axis parallel with the longitudinal axis of the work, a radially adjustable trimming point secured to said rotatable member, a member having a shank adjustable toward and from the axis of said rotatable member, and a pair of divergent guide arms and trimming points movable upon said guide arms for the purpose described.

5. A trimming mechanism for grinder wheels of shaft grinding-machines, comprising means for trimming a concave segment in the periphery of the grinder wheel, exactly corresponding to a segment of the finished work, the center of said trimming arc being in alignment with the axis of the shaft being ground.

6. A trimming mechanism for grinder wheels of shaft grinding-machines, compris-

ing means centered parallel with the longitudinal axis of the work for trimming a concave segment in the periphery of the grinder wheel, means for adjusting the radius of the trimming arc into correspondence with the radius of the finished cylindrical surface of the work ground by the grinder wheel, and edge-trimming means positioned at each side of the trimming means for forming a concave segment for fashioning adjacent portions of the grinding surface.

7. A trimming mechanism for grinder wheels of shaft grinding-machines, comprising means for trimming a concave segment in the periphery of the grinder wheel, means for adjusting the radius of said trimmer into exact correspondence with the radius of the cylindrical portion of the finished work ground by said grinder wheel, and divergent edge-trimmers for fashioning the portions of the grinder wheels at opposite ends of the concave portion and for limiting the length of arc of the latter.

8. A trimmer mechanism for grinding wheels of shaft grinding machines comprising means for holding the work to be ground and a grinding wheel, means for trimming a concaved segment in the periphery of the grinding wheel exactly corresponding to a segment of the finished work, the center of said trimming arc being in alinement with the axis of the shaft being ground, and means for mounting the trimming means whereby the wheel can be trimmed without removing the work from its holders.

9. In a shaft grinding machine, the combination with a shaft holder and a grinding wheel, adapted to relatively reciprocate, and a trimmer for the grinder wheel pivotally mounted on the machine independently of the work holding points and having a center in alinement with the axis of the shaft being ground.

10. In a shaft grinding machine, the combination with a rotary grinder wheel and reciprocatory work-holder, of a trimming mechanism comprising means for trimming a concave segment in the periphery of the grinder wheel complementary to a predetermined segment in the finished work, and a mounting for said trimmer in exactly predetermined relation to said grinder, such that the trimmed segment in said wheel is

registerable with said predetermined segment in the finished work.

11. In a machine for grinding splined shafts, a grinder wheel having a grinding surface arranged to correspond with the space between the splines, means on the machine adapted to be moved into and out of operative position with the grinding wheel for trimming a concave segment of the grinding surface of the wheel to fashion the same to accord with the shape of the finished work between the splines and means for moving said trimming means in an arc.

12. In a splined shaft grinding machine, the combination with a grinding wheel and a bed, of means for trimming a concaved segment in the periphery of the grinding wheel exactly corresponding to a segment of the finished work comprising an oscillatory support for the trimming means, the center of said trimming arc being in alinement with the axis of the shaft being ground and side trimming means associated with said other means and mounted on said bed.

13. The combination with a rotary grinder wheel and a reciprocatory work-holder, of trimming mechanism comprising means for trimming a concave segment in the periphery of the grinder wheel complementary to a predetermined segment in the finished work, edge trimming means for limiting the length of the segment and fashioning adjacent portions of the grinder, and a mounting for said trimming mechanism in exactly predetermined relation to said grinding machine, such that the trimmed segment in the grinder wheel is registerable with said predetermined segment in the finished work.

14. In a shaft grinding machine, the combination with shaft-holding centers and a grinder wheel, of means for relatively reciprocating the same, and a concave trimmer for the grinder wheel mounted on the machine independently of said work-holding centers and so positioned that the trimmed segment is registerable with a predetermined segment in the finished work.

In testimony whereof I affix my signature in presence of two witnesses.

FREDERICK ALEXANDER WARD.
